FOLDING BED FOR AUTOMOBILES

Filed Feb. 2, 1922

2 Sheets-Sheet 2

By *A. Randolph Jr.* Attorney

UNITED STATES PATENT OFFICE.

CHARLES E. DAVIS, OF BEND, OREGON, ASSIGNOR TO HANDY AUTO BED COMPANY, INC., OF BEND, OREGON, A CORPORATION OF OREGON.

FOLDING BED FOR AUTOMOBILES.

Application filed February 2, 1922. Serial No. 533,560.

To all whom it may concern:

Be it known that I, CHARLES E. DAVIS, a citizen of the United States, residing at Bend, in the county of Deschutes and State 5 of Oregon, have invented certain new and useful Improvements in Folding Beds for Automobiles; and I do hereby declare the following to be a full, clear, and exact description of the invention, such as will enable others skilled in the art to which it 10 pertains to make and use the same.

This invention relates to new and useful improvements in folding beds for automobile tourists, and has for its primary object 15 the provision of a device that may be easily and quickly applied to the running board of an automobile and when unfolded will form a comfortable rest for one or more persons with the running board acting as a support for one end of the device, and when folded will occupy a small space and may be employed as a luggage carrier if desired, or 20 may be removed from the running board and stored within the automobile.

Another object of this invention is the 25 provision of a folding bed of the above stated character which will be simple, durable and efficient, and which may be manufactured and sold at a comparatively low 30 cost.

With these and other objects in view as 35 will become more apparent as the description proceeds, the invention consists in certain novel features of construction, combination and arrangement of parts as will be 40 hereinafter more fully described and claimed.

For a complete understanding of my invention, reference is to be had to the following description and accompanying drawings, 45 in which:

Figure 1 is a top plan view, illustrating 50 a folding bed applied to an automobile and constructed in accordance with my invention,

Figure 2 is a longitudinal sectional view, 55 illustrating the bed,

Figure 3 is an end view illustrating in 60 dotted lines the device in a folded position on the running board,

Figure 4 is a side view illustrating the 65 device folded and forming a luggage carrier on the running board,

Figure 5 is a view illustrating the device

folded and removed from the running board. 55

Referring in detail to the drawings, the numeral 1 indicates a folding frame which has one end supported by being detachably secured to the running board 2 of an automobile 3 by clamps 4. The frame 1 is further supported by pairs of foldable legs 5, whereby the frame will maintain a position in horizontal alinement with the running board when in use as a bed. A bed forming member 6 has one of its ends secured to one 60 of the ends of the frame 1 and its other end secured to clamps 4 employed for attaching the frame to the running board. The bed forming member 6 is preferably constructed 65 of fabric and is supported intermediate its ends by means of coil springs 8 that are attached to the side members of the frame 1 by rings 9. If desired, a mattress may be placed on the bed forming member 6 to render the device more comfortable to the user. 70

The folding frame comprises side members 10, each including sections 11 and 12 that have their adjacent ends connected to T-shaped elements 13 which are in turn connected to T-shaped elements 14 carried by or connected to a transversely extending bar 15 and the T-shaped elements 14 also have one pair of legs 5 attached thereto. The sections 11 constitute extensions of section 12 and are disposed in a plane above the sections 12 and 85 are connected to the T-shaped elements 13 by L-shaped elements 16. The sections 11 and 12 and the L-shaped elements are preferably constructed from pipes having threaded connection with each other. The 90 L-shaped elements are threaded to the T-shaped elements 13 so that the sections 11 may be swung parallel with the transverse bar 15 when desiring to fold the device. The sections 12, owing to the T-shaped ele- 95

ments 13 having separate connections with the T-shaped elements 14, may be swung parallel with the bar 15. The legs 5 connected to the T-shaped elements 14, are preferably constructed of pipes threaded into L-shaped elements 17 that have threaded connection with the T-shaped elements 14 to permit the legs to be moved into folded or extended position as desired. The other ends of the sections 11 are threaded 100 to T-shaped elements 18 to which the other pair of legs are connected. The last named pair of legs are constructed from pipes 105

threaded to L-shaped elements 19 that have threaded connection with the T-shaped elements 18 so that said legs may be extended or folded as desired. The T-shaped elements 18 also receive a transverse rod 20 to which one end of the bed forming member 6 is secured and the rod 20 is removable from the T-shaped elements 18 so that the member 6 may be folded when desired.

10 The sections 12 of the side members 10 carry L-shaped elements 21 that extend through openings in the clamps 4. The clamps 4 are of substantially U-shape adapted to be positioned over the outer edge of the 15 running board and secured to said running board by set screws 22. The clamps are preferably constructed of channel iron and one of their arm portions is provided with spaced notches 23 adapted to receive the 20 ends of a rod 24 that has the other end of the bed forming member 6 secured thereto. By having a series of notches it permits the 25 rod 24 to be adjusted along the clamps for the purpose of placing the desired tension on the bed forming member 6 when in a bed forming position. Also it will be realized that the entire structure may be raised from elements 21 as pivots or an axis thus providing slack in element 6 so that when the frame 30 is thus raised, the rod 24 may be more readily engaged in notches 23. When the frame is lowered, element 6 will be stretched or tensioned from end to end.

To fold the device upon the running board 35 for the purpose of forming a luggage carrier, the rod 20 is detached from the T-shaped element 18 and the legs connected to said element are swung in parallelism with the sections 11 and said sections are turned 40 in parallelism with the transverse bar 15. The sections 12 are then swung upwardly or into a vertical position upon the running board so that luggage may be placed between the side of the automobile and the bed 45 forming element and be prevented from dislodging from the automobile during transit. The pair of legs connected to the T-shaped elements 14 may be swung in parallelism with the connection between the sections 11 and the bar 15 for the purpose of preventing 50 any part of the device from protruding beyond the outer edge of the running board of the automobile. If not desiring to employ the device as a luggage carrier, the device 55 may be easily and quickly removed from the running board by detaching the clamps from the running board and to store the device in the automobile, the device is first folded in a manner heretofore described 60 and after the folding of the sections 11 in parallelism with the bar 15, the sections 12 are swung in parallelism with the bar 15.

While I have shown and described the preferred embodiment of my invention, it 65 will be understood that minor changes in

construction, combination and arrangement of parts may be made without departing from the spirit and scope of the invention.

Having thus described my invention, what I claim is:

1. A device of the class described comprising a frame having a section adapted to assume either a substantially horizontal or an upstanding position, means for connection of said section to a running board, extension means for the frame utile in a substantially horizontal position when said section is substantially horizontal and in said position adapted to cooperate with said section to provide a bed frame, the extension means having its component parts foldable into compact relation to the said section whereby the said section in an upstanding position may form a luggage carrier, and a bed forming element including means normally maintaining the component parts of said extension means in bed forming relation. 70 80 85

2. A device of the class described comprising a frame having a section adapted for disposition in an upstanding position relative to a running board to form a luggage carrier, extension means for the frame having parts in foldable relation to the said section in the said position, said section and said extension means being movable to substantially a horizontal position, a bed-forming element to cooperate with said section and extension means in the substantially horizontal position, said bed-forming element having means cooperating with the parts of the extension means to maintain them in bed-frame relation and against folding, and means engageable with the ground to support the said section and extension means in said substantially horizontal position. 90 95 100 105

3. A folding bed for automobile tourists comprising a collapsible frame, bed forming elements yieldably secured to said frame intermediate its ends and having one end detachably secured to one end of the frame, clamps secured to the other end of the frame, means adjustably securing the other end of the bed forming element to said clamps, means securing said clamps to the running board of an automobile, and collapsible legs carried by the frame. 110 115

4. A device of the class described including attaching means, side members, each side member consisting of a rear section and a forward section pivoted together, the rear sections being pivoted to said attaching means for raising and lowering movement, the forward sections being foldable in substantial parallelism transversely of the device, a bed-forming means having detachable connection with the forward sections, means carried by the bed-forming element engageable with the attaching means when the forward and rear section are in raised 120 125 130

position and whereby said bed forming element will be tensioned as said forward and rear sections are lowered.

5. A device of the class described including side members, each side member consisting of a rear section and a forward section pivoted to the rear section, said forward sections being foldable into substantial parallelism transversely of the device, and foldable 10 bed-forming means associated with the forward sections to normally prevent folding thereof.

6. A device of the class described including side members, each side member consisting of a rear section and a forward section pivoted together, a bar connecting the rear sections, said forward sections being foldable into substantial parallelism with said bar, legs for said sections, and foldable bed-forming means associated with the forward sections to normally prevent folding thereof.

7. A device of the class described including attaching clamps, side members, each

side member consisting of a rear section and a forward section pivoted together, said rear sections being pivoted to said attaching clamps for raising and lowering movement, a bar connecting the rear sections, the forward sections being foldable into substantial parallelism with said bar, a bed-forming means having a rod detachably connected to the forward sections, said attaching clamps having notches, means carried by the bed-forming element to engage said notches when the forward and rear sections are raised, whereby said bed-forming element will be tensioned as said forward and rear sections are lowered, and legs for the forward and rear sections.

In testimony whereof I affix my signature 40 in presence of two witnesses.

CHARLES E. DAVIS.
